IGNITION APPARATUS

Application filed March 15, 1929. Serial No. 347,432.

This invention relates to improvements in ignition devices for internal combustion engines, and particularly to such devices adapted to vary the timing of the sparking impulses for said engines.

It is among the objects of the present invention to provide a device adapted automatically to control the time of sparking impulses in accordance with the speed of the engine.

A further object is to provide a device capable of adjusting the aforementioned speed control device in accordance with the temperature conditions of the engine.

Further objects and advantages of the present invention will be apparent from the following description, reference being had to the accompanying drawings, wherein a preferred form of embodiment of the present invention is clearly shown.

In the drawings:

Fig. 1 is a plan view of a timer distributor mechanism having the distributor head and rotor removed.

Fig. 2 is an enlarged fragmentary, sectional view taken along the line 2—2 of Fig. 3, showing the method of pivotally supporting the centrifugal element.

Fig. 3 is a vertical, sectional view taken through the ignition device.

Fig. 4 is a fragmentary view showing the centrifugal member and the adjusting means therefor.

Fig. 5 is a detail view of the timer cam unit to which is secured the dependent advance cam member which coacts with the centrifugal ring to change the angular relation between the timer cam and its drive shaft.

Fig. 6 is a detailed, fragmentary view showing the one end of the thermostatic element to which one end of the coil spring of the centrifugal member is attached.

Referring to the drawings and particularly to Fig. 3, the ignition device is shown comprising a cup-shaped casing 20, having a tubular extension 21, which is adapted to fit into a recess provided in the body of the engine for supporting the ignition device upon said engine. A tubular extension 22,

coaxial with the extension 21, is inside the casing 20 and provides for an elongated bearing in which the shaft 23, driven by the engine, is journaled. Shaft 23 has a portion 24 of lesser diameter than the portion of the shaft journaled in the bearings 21 and 22.

A collar 25 is secured to the drive shaft 23 by a pin 26, which extends through the shaft and collar. Collar 25 has a depending annular flange 27, which surrounds the upper end of the bearing extension 22, as shown in Figs. 2 and 3. Diametrically opposite openings 28 are provided in the annular flange 27 of the collar 25, these openings 28 being substantially coaxial in alignment and being adapted to receive the reduced ends of pivot pins 29, which are secured in the centrifugal member 30 and pivotally support said member on the collar 25. From this it may be seen that the centrifugal member 30 rotates with the engine driven shaft 23, for said member is carried by the collar 25 which is secured to shaft 23 by the cross pin 26. Centrifugal member 30 has a screw 31 provided with a reduced extension 32 at its other end which extends beyond the inner surface of the ring or centrifugal member 30.

Upon shaft portion 24 which, as has been mentioned heretofore, is of lesser diameter than the shaft portion journaled in the bearings 21 and 22, there is mounted the distributor rotor 33 and the timer cam 34, a pin 35 connecting the cam with the rotor so that they are rotated in unison. Both the cam and rotor are rotatably supported upon the shaft portion 24. To the end of the cam 34, adjacent the collar 25, there is secured a member 36 having an arcuate skirt portion 37, which is substantially concentric with the axis of the pivot pins 29 of the centrifugal member 30. In this arcuate skirt 37 there is provided a slot 38 angular to the axis of the shaft 23, into which the reduced portion 32 of screw 31 extends, said screw being carried by the centrifugal member 30. The slot 38 is angular to the path in which portion 32 of screw 31 moves when the centrifugal member 30 is moved about its pivot pins 29 so that, as the portion 32 of the screw 31 moves through the angular slot 38, the member 36,

secured to cam 34, will be rotated relative to shaft 23 and thus, cam 34 is rotated relative to said shaft 24, so that the time of sparking impulses is altered in accordance with the movement of the centrifugal member 30.

In Fig. 1, the circuit interrupter, operated by cam 34, is illustrated. This interrupter comprises a movable contact 40 supported on arm 41 pivoted on the pin 42, the arm having a rubbing block 43 maintained in engagement with the cam 34 by a spring 44. Movable contact 40 cooperates with the stationary contact 45 supported on the bracket 46.

One of the pivot pins 29 supports a disk 50 which is cup-shaped, the peripheral edge of said disk being provided with serrations 51 which bite into the centrifugal member 30 when the pivot pin 29, which supports the disk, is turned tightly to clamp said disk upon the ring. Normally the centrifugal member 30 is urged to align with the axis of shaft 23 as shown in the Figs. 3 and 4. The centrifugal member is urged into this position by a coil spring 60 surrounding the pivot pin which supports the disk 50. One end of the coil spring is anchored to an end of the cross pin 26 extending beyond the confines of the collar 25. The other end of the spring 60 is attached to one end of the thermostatic member 61. The opposite end of said thermostatic member is secured to a pin 62 carried by the disk 50. The thermostatic member 61 is made of bimetal and is adapted to expand and contract with increasing and decreasing temperatures respectively. The end of the thermostatic member 61 to which spring 60 is secured has an angular ear 63 which extends into and through an opening 64 in the outer face of the disk 50, said opening being of a predetermined length, whereby the movement of the thermostatic member 61 will be limited.

The tension of the spring 60 may initially be set as desired through the manual operation of the disk 50. If the tension of the spring is to be increased, pivot pin 29 is unscrewed, thereby releasing the disk 50 which may then be rotated in the proper direction to increase the tension of the spring 60. When the proper tension is attained, the pivot screw 29 is again tightened causing the serrations 51 to bite into the ring 30 and thus maintain the disk in the properly adjusted position. The thermostat automatically adjusts the tension of the spring in accordance with the temperature of the engine. It has been found that a cold engine will start more quickly, run better, and idle more smoothly if the time of sparking impulses is advanced beyond the limits allowable when the engine is warm. For this reason, the thermostat has been provided for adjusting the centrifugal device, said thermostat being affected by increasing temperatures of the engine to increase the tension of the spring whereby the

centrifugal element may move through a proper range to adjust the time of sparking impulses for a warm engine. On the other hand, when the engine is cold, the thermostat 61 will be affected to decrease the spring tension permitting the centrifugal member to move more freely to a greater spark advancing position and thus, the time of sparking impulses will be advanced to a substantially greater degree than for normal warm engine operation.

The present invention provides for the automatic adjustment of the spark timing device, whereby the time of sparking impulses may be properly set for varying engine temperatures and thus more efficient engine operation is obtained.

While the form of embodiment of the present invention as herein disclosed, constitutes a preferred form, it is to be understood that other forms might be adopted, all coming within the scope of the claims which follow.

What is claimed is as follows:

1. An ignition device for an internal combustion engine comprising, in combination, a timer; speed controlled means for adjusting the timer to vary the time of sparking impulses in accordance with engine speeds; yieldable means normally urging the speed controlled means toward the spark retarding position; and thermostatic means adapted to vary the tension of the yieldable means in accordance with the engine temperatures.

2. An ignition device for an internal combustion engine comprising, in combination, a timer; speed controlled means for adjusting the timer to vary the time of sparking impulses in accordance with engine speeds; a coil spring normally urging the timer adjusting means toward the normal, spark retarding position; and means controlled by varying engine temperatures for varying the tension of the coil spring in accordance with said engine temperatures.

3. An ignition device for an internal combustion engine comprising, in combination, a timer; speed controlled means for adjusting the timer; and means operable at varying engine temperatures to vary the effect of the speed controlled means.

4. An ignition device for an internal combustion engine comprising, in combination, a timer; a centrifugal governor for automatically adjusting the timer in accordance with varying engine speeds; a spring urging the centrifugal governor toward the normal spark retarding position; manually operable means for adjusting the tension of the spring; and thermostatic means adapted automatically to change the tension of the spring in accordance with engine temperatures.

5. An ignition device for an internal combustion engine comprising in combination, a timer including a circuit interrupter and a

cam for operating it; an engine driven shaft; a speed governor carried on and driven by said shaft said governor connecting the cam with the shaft and being adapted to rotate the cam relative to said shaft in accordance with the speed of the engine for varying the time of sparking impulses; a spring urging the speed governor into the normal spark retarding position; a manually operable member for adjusting the tension of the spring; and a thermostatic element interposed between the manually operable member and the spring automatically varying the tension of the spring in accordance with engine temperatures.

6. An automatic spark timing device for an internal combustion engine, comprising in combination, an engine driven shaft; a cam supported on said shaft so as to be rotatable relative thereto; a circuit interrupter adapted to be operated by said cam; centrifugally operated means pivotally carried by the shaft and having provisions for connecting the cam with the shaft, said means being adapted, in response to varying speeds of the engine, to alter the angular position of the cam relative to the shaft; a spring yieldably urging the centrifugal means into normal position; and temperature controlled means for varying the tension of said spring in accordance with temperature conditions.

7. An automatic spark timing device for the ignition system of an internal combustion engine, comprising in combination, an engine driven shaft; a breaker cam rotatably mounted on said shaft; an arcuate member provided with a spiral slot, secured to the cam; a sleeve secured to the drive shaft; a centrifugal member pivotally secured to the sleeve and operatively connected with the spiral slot of the arcuate member; a spring anchored at one end of the sleeve; a thermostatic member anchored at one end to the centrifugal member and at the other end to the free end of the spring whereby temperature changes will vary the tension of the spring which normally urges said centrifugal member into spark retarding position.

8. An automatic spark controlling device for an internal combustion engine, comprising in combination, a drive shaft; a centrifugal member pivotally mounted thereupon; a coil spring urging said centrifugal member into normal position; means for manually adjusting the tension of said coil spring; and means for automatically adjusting the tension of said coil spring in accordance with temperature conditions.

9. An automatic spark controlling device for an internal combustion engine, comprising in combination, a drive shaft; a centrifugal member pivotally mounted thereupon; a disc supported by one of the pivots of the centrifugal member so that it will move with said member; a coil spring adapted to urge

the centrifugal member into normal position said spring having one end anchored to the drive shaft; thermostatic means secured at one end to the free end of the spring the other end of the thermostatic member being anchored to the disc whereby the tension of the spring may be varied automatically by the thermostatic means in accordance with temperature changes or by the manual adjustment of the disc.

10. An ignition device for an internal combustion engine comprising in combination: a circuit interrupter; a cam for operating said interrupter; a drive shaft; and temperature responsive means for connecting the drive shaft and cam and for varying the angular relation between them.

11. An ignition device for an internal combustion engine comprising in combination: a circuit interrupter; a cam for operating said interrupter; a drive shaft; and devices responsive to varying temperature and engine speeds for connecting the drive shaft and cam and for varying the angular relation between them in accordance with such temperature and speed variations.

In testimony whereof I hereto affix my signature.
